(57) CLAIM

The ornamental design for a wrinkle prevention pillow, as shown and described.

DESCRIPTION

FIG. 1 is a perspective view of an embodiment of the wrinkle prevention pillow;

FIG. 2 is a front elevational view of the wrinkle prevention pillow;

FIG. 3 is a rear elevational view of the wrinkle prevention pillow;

FIG. 4 is a left side elevational view of the wrinkle prevention pillow;

FIG. 5 is a right side elevational view of the wrinkle prevention pillow;

FIG. 6 is a top plan view of the wrinkle prevention pillow;

FIG. 7 is a bottom plan view of the wrinkle prevention pillow;

FIG. 8 is a partial cross-sectional view of the wrinkle prevention pillow taken along lines 8-8 of FIG. 6;

FIG. 9 is a partial cross-sectional view of the wrinkle prevention pillow taken along lines 9-9 of FIG. 2; and, FIG. 10 is another perspective view of the wrinkle prevention pillow in use.

The broken lines shown in FIGS. 9, 10 are included for the purpose of illustrating environmental elements only and form no part of the claimed design.

1 Claim, 7 Drawing Sheets
